UNITED STATES PATENT OFFICE.

GEORGE M. LIGHT, OF POMEROY, WASHINGTON.

DESIGN FOR A HAME ATTACHMENT.

SPECIFICATION forming part of Design No. 32,540, dated April 17, 1900.

Application filed March 2, 1900. Serial No. 7,129. Term of patent 14 years.

To all whom it may concern:

Be it known that I, GEORGE M. LIGHT, a citizen of the United States, residing at Pomeroy, in the county of Garfield and State of Washington, have invented and produced a new and original Design for a Hame Attachment, of which the following is a specification.

This invention relates to a new and useful design for a harness attachment, and the essential features reside in an elongated body having an inner concaved face and a series of outstanding parallel projections of rectangular form spaced apart from each other in a regular manner in a vertical direction.

In the drawings, Figure 1 is a perspective view of a hame attachment embodying the features of the design. Fig. 2 is a transverse vertical section of the attachment.

The numeral 1 designates a body which is reduced in a transverse direction between enlarged upper and lower ends 2 and 3 by a concave inner edge or face 4, and from the lower end 3 depends an ear 5, having an outer curved edge 6, opposite flat faces 7, converging toward the bottom of the ear and a trans-

verse circular opening 8. The upper end 2 of the body 1 also has an opening 9 extending therethrough in a plane at right angles to the direction of the opening 8, and the outer side edge of the said body has a series of horizontally-disposed rectangular projections arranged in vertical alinement with spaces of regular dimensions between and each having a vertical opening 11 therethrough. The outer edge of the body 1 between the projections 10 is concaved, as at 12, and in the body intermediate of its ends are transverse openings 13, having the same direction as the opening 9 in the head 2.

Having thus described the invention, what is claimed as new is—

The design for a hame attachment, herein shown and described.

In testimony that I claim the foregoing as my own I have hereto affixed my signature in the presence of two witnesses.

GEORGE M. LIGHT.
